UNITED STATES PATENT OFFICE.

CHARLES W. KAYSER, OF BOSTON, MASSACHUSETTS.

DESIGN FOR A BIB.

SPECIFICATION forming part of Design No. 32,461, dated April 3, 1900.

Application filed March 1, 1900. Serial No. 7,025. Term of patent 14 years.

To all whom it may concern:

Be it known that I, CHARLES W. KAYSER, a citizen of the United States, residing at Boston, in the county of Suffolk and State of Massachusetts, have invented and produced 5 a new Design for Bibs, of which the following is a specification, reference being had to the accompanying drawing, forming a part thereof.

As shown in the drawing, the leading and essential feature of my design consists of the substantially-inverted shield-shaped upper portion and a lower portion, the lower portion connected to the lower edge of the upper

portion and projecting laterally upon each 15 side of the connection.

Having described my invention, I claim as new and desire to secure by Letters Patent of the United States—

The design for a bib substantially as herein 20 shown and described.

In testimony whereof I have hereunto set my hand this 27th day of February, 1900.

CHAS. W. KAYSER.

In presence of—

T. HART ANDERSON,
CHRISTIANA KITCHING.
